(57) **CLAIM**

The ornamental design for a standard mouth straw lid, substantially as shown and described.

DESCRIPTION

FIG. 1 is a top, front and right side perspective view of a standard mouth straw lid, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, front and right side perspective view with the standard mouth straw lid expanded; and,

FIG. 9 is a bottom, rear and left side perspective view with the standard mouth straw lid expanded.

The broken lines in FIGS. 1, 6, 7, and 8 depict portions of the standard mouth straw lid that form no part of the claimed design.
